L. BINNS.
WOVEN CHENILLE FABRIC.

No. 545,334.

Patented Aug. 27, 1895.

UNITED STATES PATENT OFFICE.

LEEDHAM BINNS, OF PHILADELPHIA, PENNSYLVANIA.

WOVEN CHENILLE FABRIC.

SPECIFICATION forming part of Letters Patent No. 545,334, dated August 27, 1895.

Original application filed March 7, 1894, Serial No. 502,650. Divided and this application filed December 13, 1894. Serial No. 531,699. (No model.)

To all whom it may concern:

Be it known that I, LEEDHAM BINNS, of Philadelphia, county of Philadelphia, and State of Pennsylvania, have invented a new and Improved Woven Chenille Fabric, of which the following is a full, clear, and exact description.

The invention relates to woven chenille fabrics such as shown and described in the Letters Patent of the United States No. 514,809, granted to me on February 13, 1894, and in the application for Letters Patent of the United States, Serial No. 502,650, filed by me on March 7, 1894, and of which this application is a division.

The object of the invention is to provide a new and improved chenille fabric having a fine appearance and adapted to be formed in various ways to produce a large variety of styles.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the views.

Figure 1 is a sectional side elevation of an uncut fabric embodying the improvement. Fig. 2 is a like view of the same as cut on opposite sides of the web, showing the finished strand of chenille. Fig. 3 is a sectional side elevation of a modified form of the improvement, showing the sets of warp arranged alternately on opposite sides of the web. Fig. 4 is a like view of the same as cut, and showing the finished strand of chenille. Fig. 5 is a sectional side elevation of another modified form of the improvement, showing the set of warps arranged on one side of the web only. Fig. 6 is a like view of the same as cut, showing the finished strand of chenille. Fig. 7 is a sectional side elevation of a third modified form of the improvement, showing a central web without the central warp and the wefts crossed between the sets of warps; and Fig. 8 is a similar view of a fourth modified form, showing a central web with a central warp and the wefts crossed between the sets of warps.

The improved woven chenille fabric, as illustrated in Figs. 1 and 2, is provided with a central warp A and sets of warps arranged on opposite sides of the central warp and in a different plane above and below a web F, as will be readily understood by reference to the said figures. On one side of the central warp A and a suitable distance below the web F is arranged a set of warps B, comprising three or more threads and bound by the weft-threads C, which extend upwardly from the innermost thread of the set of warps B to pass over the said central warp A, and then to the other side thereof to bind in a second set of warps B', arranged directly below the web F, but in a different horizontal plane to that in which the sets of warps B are located. The two warps B and B' are thus bound by the same weft-threads C, but a suitable distance apart, on opposite sides of the warp A, below the web F and in a different horizontal plane.

Directly above the set of warps B is arranged another set of warps B², preferably containing the same number of threads as the set of warps B, and these warps B² are bound by weft-threads C', which likewise extend upwardly and pass over the central warp A', to then pass downward on the other side of the said central warp to bind the set of warps B², located directly below the set of warps B' and in the same horizontal plane as the warps B². Above the latter and directly below the web F is arranged a set of warps B³, bound in by weft-threads C², also passing over the central warp A, to then pass downward on the opposite side thereof to bind in a set of warps B³, located below the warps B² and in the same horizontal plane in which the warps B are located. A similar arrangement of warps and wefts is arranged above the web F—that is, a set of warps D is bound in by weft-threads C³, passing under the central warp A to the other side thereof, to then extend upwardly to bind in a set of warps D', and above the set of warps D is arranged another set of warps D², bound in by the weft-threads C⁴, also passing under the central warp A, to rise on the other side to bind in a set of warps D², located below the warps D', as is plainly shown in Fig. 1. Above the warps D² is ar-

ranged another set of warps D⁴, bound in by weft-threads C⁵, extending downwardly and passing under the central warp A, to rise on the other side thereof to bind in a set of warps 5 D⁵, arranged under the set of warps D³ and directly above the web F.

The weft-threads C, C', C², C³, C⁴, and C⁵, after leaving the warps B' B³ B⁵ D' D³ D⁵, respectively, bind in second sets of warps B B² 10 B⁴ D D² D⁴, respectively, in the manner above described, to then pass over and under a second central warp A, as above described and shown in Fig. 1. The entire fabric, throughout its width, is composed of such sections, 15 each comprising sets of warps bound by the wefts, as has been described, it being understood that some of the wefts pass over a central warp and some of them pass under the same from a set on one side of the central 20 warp to a set of warps on the other side of the said central warp. It will be understood that the wefts form bends where they pass over or under the central warps.

The central warps A are held in position in 25 the web F by a weft f³ of the set of warps, binding in addition the two sets of warps F' and F², arranged on opposite sides of the central warp A and in alignment therewith. Now, by cutting the weft-threads above and 30 below the web F, between two adjacent sections, as indicated by the cutting-line shown in Fig. 1, a fabric is produced having one half of the warps and their binding wefts extending above the said web, while the other half 35 extend below the same, as indicated in Fig. 2, and from this fabric strands of chenille are produced by cutting it longitudinally, the strands having the appearance shown in Fig. 2. The cut ends of the wefts form tufts, so as 40 to form a complete circular fabric, as the cut ends of the wefts spring back to the position shown in Figs. 2 and 6, in line with the row of warp-threads of the set they bind. It is 45 understood that when the wefts are cut between two sections, the ends of the wefts projecting from the uppermost warp-threads must spring back to the position described, as there is then no connection with the warps 50 of the next following section, and consequently they have no support for holding the same in the inclined position shown in Fig. 1. Thus a fabric is produced having a central warp arranged in a longitudinally-extending continuous web, and with wefts passing 55 around the central warp above or below the web, as will be readily understood by reference to Fig. 2. When this fabric is cut into strands, as hereinbefore mentioned, the continuous or ground web is divided into a series 60 of cords connecting the tufts of chenille formed by the radiating sets of warp-pieces and the wefts interwoven therewith.

As illustrated in Fig. 3, the sets of warps are arranged alternately on opposite sides of 65 a web F⁴, similar in construction to the web F, previously described, the central warps A³ and A⁴ forming part of said web. The sets

of warps G and G' are located on opposite sides of the central warp A³, but below the web F⁴, while the next following set of warps G³ and G⁴, for the central warp A⁴, are located above the web F⁴, as plainly illustrated in the said Fig. 3. The weft-threads G² for the sets of warps G and G' pass over the central warp A³ and then extend below the web F⁴, while 70 the weft-threads G⁵ for the sets of warps G³ and G⁴ pass under the adjacent central warp A⁴ and extend above the web F⁴. Now, by cutting the weft-threads G² and G⁵ opposite the respective central warps A⁴ or A³, a fabric is produced, as shown in Fig. 4, having the sets of warps and their weft-threads extending alternately on opposite sides of the web F⁴, with the corresponding central warps A³ or A⁴ as the center. 85

As illustrated in Fig. 5, the central warps A⁵ are likewise bound in a web F⁵, similar in construction to the webs F⁴, previously described, and the sets of warps H and H' and their binding weft-threads H² are all arranged 90 on one side of the said web F⁵, so that on cutting the weft-threads H² between the adjacent sections of the fabric a fabric such as shown in Fig. 6 is produced, having sets of warps and wefts on one side of the web F⁵ 95 only.

As illustrated in Fig. 7, the central warps are entirely dispensed with and only a web F⁶ is employed, with sets of warps I and I' arranged below the said web, and warps I² and I³ arranged above the said web, with the binding wefts I⁴ for the warps I passing to the set of warps I⁵ to bind the same, while the other weft-threads I⁵ for the warps I² cross and pass through and bind the warps I' below the web 105 F⁶. By this arrangement the weft-threads I⁴ and I⁵ cross each other in the web F⁶, and the fabric is cut between the adjacent sections above and below the web F⁶, by cutting the wefts I⁴ and I⁵. 110

As illustrated in Fig. 8, the fabric is formed in the cross weft-threads with a central warp A⁶, arranged in the web F⁷, but otherwise this fabric is the same as the one shown in Fig. 7. 115

Having thus fully described my invention, I claim as new and desire to secure by Letters Patent—

1. As a new article of manufacture, a woven chenille fabric comprising a web, central warps within the said web, separate sets of warps on opposite sides of the said central warps and on opposite sides of the said web, wefts binding the said separate sets of warps some of the wefts passing over the said central warps of the web and binding the separate sets of warps on one side of the web, and the remainder of the wefts passing under the said central warps and binding the separate sets of warps on the other side of the web, the ends of the wefts projecting from the outermost warp threads in the several sets on each side of the web, to form tufts, substantially as shown and described. 120 125 130 135

2. As a new article of manufacture, a woven chenille fabric comprising a continuous web, separate sets of warps arranged at intervals laterally of the said web, and wefts interwoven with the said separate sets of warps, the ends of the wefts projecting from the outermost warp threads to form tufts, substantially as described. 40
3. As a new article of manufacture, a woven chenille fabric comprising a continuous web, separate sets of warps arranged at intervals laterally of the said web, central warps located in the web at the intervals separating the said sets of warps, and wefts interwoven with the central warps and the separate sets of warps, the ends of the wefts projecting from the outermost warp threads to form tufts, substantially as described. 45
4. As a new article of manufacture, a woven chenille fabric comprising a continuous web, separate sets of warps arranged at intervals on opposite sides of the said web, and wefts interwoven with the said separate sets of warps, the ends of the wefts projecting from the outermost warp threads to form tufts, substantially as described. 50
5. As a new article of manufacture, a woven chenille fabric comprising a continuous web, separate sets of warps arranged at intervals on opposite sides of the said web, central warps located in the web at the intervals separating the said sets of warps, and wefts interwoven with the central warps and the separate sets of warps, the ends of the wefts projecting from the outermost warp threads to form tufts, substantially as described. 55
6. A strand of chenille, comprising a continuous cord, separate sets of warps radiating at intervals from the said cord, and wefts interwoven with the said sets of warps, the ends of the wefts projecting from the outermost warp threads to form tufts, substantially as described. 60
7. A strand of chenille, comprising a continuous cord, separate sets of warps radiating at intervals from the said cord on opposite sides of the same, and wefts interwoven with the said sets of warps, the ends of the wefts projecting from the outermost warp threads to form tufts, substantially as described. 65
8. A strand of chenille, comprising a continuous cord, central warps located in the cord at intervals, separate sets of warps radiating from the said central warps, and wefts interwoven with the said sets of warps and extending toward the central warps, the ends of the wefts projecting from the outermost warp threads to form tufts, substantially as described. 70
9. A strand of chenille, comprising a continuous cord, central warps located in the cord at intervals, separate sets of warps radiating from the said central warp on opposite sides of the cord, and wefts likewise radiating from the said central warps on opposite sides of the cord and interwoven with the said sets of warps, the ends of the wefts projecting from the outermost warp threads to form tufts, substantially as described. 75
